ISRAEL FOSTER, OF PHILADELPHIA, PENNSYLVANIA.

Design No. 3,200, dated September 22, 1868.

DESIGN FOR A CARPET-PATTERN.

The Schedule referred to in these Letters Patent and making part of the same.

TO ALL WHOM IT MAY CONCERN:

Be it known that I, ISRAEL FOSTER, of the city and county of Philadelphia, State of Pennsylvania, have invented or produced a new and original Design for a Carpet-Pattern; and I do hereby declare that the accompanying drawing, and the following explanation thereof, form a full, clear, and exact description of the said design.

The figure in the drawing represents sufficient of a carpet to illustrate the design.

A represents part of the body of the carpet, and B the border.

The body is ornamented with a number of spots, of a form and arrangement clearly shown in the drawing.

Near the outer edge of the border are the three waved stripes, *a*, and a short distance from the latter is a single waved stripe, *b*, and next is an ornament composed of a row of spots, *d*, on a dark ground. After an interval, from *y* to *z*, of plain fabric, the above-described ornaments are repeated before the border meets the body of the fabric.

Irrespective of the colors employed, I claim—

The design for carpet-pattern, substantially as described, and represented in and by the accompanying drawing.

In testimony whereof, I have signed my name to this specification in the presence of two subscribing witnesses.

ISRAEL FOSTER.
